UNITED STATES PATENT OFFICE.

JONAS EMIL LARSON, OF HAMMOND, INDIANA, ASSIGNOR TO CHAMPION AUTO EQUIPMENT COMPANY, OF HAMMOND, INDIANA, A CORPORATION OF INDIANA.

DESIGN FOR AN AUTOMOBILE BODY.

Application filed January 29, 1927. Serial No. 20,543. Term of patent 14 years.

To all whom it may concern:

Be it known that I, JONAS EMIL LARSON, a citizen of the United States, residing at Hammond, in the county of Lake and State of Indiana, have invented a new, original, and ornamental Design for Automobile Body, of which the following is a specification, reference being had to the accompanying drawing, forming part thereof.

In said drawing Fig. 1 is a perspective

view of an automobile body, looking toward the front thereof, showing my new design; Fig. 2 is a side elevation thereof, and Fig. 3 is a perspective view looking at the back thereof.

I claim:

The ornamental design for an automobile body as shown.

JONAS EMIL LARSON.
